UNITED STATES PATENT OFFICE.

ALONZO NOTEMAN, OF TOLEDO, OHIO.

PORTABLE STEAM BORING-ENGINE.

SPECIFICATION forming part of Letters Patent No. 273,136, dated February 27, 1883.

Application filed May 17, 1882. (No model.)

To all whom it may concern:

Be it known that I, ALONZO NOTEMAN, a citizen of the United States, residing at Toledo, in the county of Lucas and State of Ohio, have invented certain new and useful Improvements in Portable Steam Boring-Engines, of which the following is a specification, reference being had therein to the accompanying drawings, and in which—

10 Figure 1 is a side elevation of my improved portable engine, specially adapted to drive augers or similar cutting-instruments or screw-drivers. Fig. 2 is a side elevation, and Fig. 3 is a vertical elevation, of the same; and Fig. 4 is a detail view.

15 This invention has relation to improvements in portable engines specially adapted to drive auger-drills or like boring-instruments or screw-drivers; and it consists of a shaft having one end connected to a cylinder having pistons capable of movement into and out of said cylinder within an eccentric steam-chamber, and its other end provided with a pinion and rotating in a sleeve fixed to the engine-cylinder, and upon which is mounted, also, a sleeve or bearing having a shaft provided with a larger pinion gearing with the aforesaid pinion, and capable of receiving the auger or boring-instrument or screw-driver.

20 It consists, secondly, of a chambered valve adapted to be adjusted or shifted to either one of two steam-passages of the engine, and having an exhaust port or passage to enable the reversal of the action of the engine-pistons; and, thirdly, of special mechanism to effect the reversing operation, and details of construction, substantially as hereinafter more fully set forth and claimed.

25 To carry out my invention I employ an outer cylinder, A, constructed in the usual manner as steam-cylinders in general, saving for convenience it may be cast into two parts or halves, dividing it transversely about centrally of its length, and with suitable flanges to permit them to be readily bolted together. Cast similarly and with the halves of the cylinder A is a supplemental cylinder, A', the two being thus connected together.

30 Within the cylinder A is arranged an eccentric steam-chamber, B, which is connected by two steam-passages—a live-steam passage, a, and an exhaust-passage, a'—with the chamber

b of the cylinder A', into which the steam enters through a supply-pipe, c, at its bottom.

C is a cylinder capable of rotating in the eccentric chamber B, and arranged to bear at a central point between the passages a a'. It has two pistons or wings, d d, fitted to slide in and out of said cylinder, and to separately receive the impact of steam, and thus be carried around by it from the live-steam passage a, which accordingly affect the cylinder C, and consequently cause it to rotate, as will be readily understood.

35 To the piston-cylinder C is secured the inner end of a shaft, D, bearing in a sleeve, e, projecting from one head of the outer cylinder or casing, A.

40 Upon the outer end of the shaft D is a pinion, f, which meshes with a larger pinion, f', affixed to the auger-drill or other boring or screw-driver spindle-receiving shaft g. The latter is journaled in a bearing or sleeve, h, supported or mounted, as shown or otherwise, upon the sleeve e of the shaft D.

45 It is obvious that from the foregoing arrangement a rotary motion will be imparted to the boring-instrument or screw-driver, whichever may be used, as the cylinder-pistons are acted upon by the steam in the eccentric chamber B. Oil-cup i is provided to keep the shaft D properly lubricated.

50 At the opposite end of the outer cylinder or casing, A, is secured, by a screw and sleeve fitted upon a projection thereat, a bar or rod, to which is secured a rest, j, to enable the convenient resting of the engine intact with the body of the operator. It is supported by a strap, j', or other suitable medium passed around the neck of the operator, and connected to spring-snaps j², hooked into the eyes of staples j³ on the sides of the casing A, or in other suitable manner.

55 E E' are hand-rods connected by cross-rods k, suitably fastened to the casing A, to enable the convenient handling of the engine in manipulating the drill, boring instrument or screw-driver.

60 F is the reversing-valve, adjusted to partially rotate or permit of shifting its open chamber F' from one steam-passage to the other of the passages a a' upon an exhaust pipe or tube, l, centrally arranged in the steam-chamber b, as clearly shown in Figs. 2 and 3. The chamber

F' of the valve F, which, as above intimated, opens into either of passages a a', exhausts through the axial pipe l.

The mechanism to permit the reversing of the valve F, which is necessary, in order to reverse the action of the engine when it is desired to withdraw the auger or implement, consists of a toggled lever, G, one arm or link, connected to a sleeve, m, of the valve, fitted to turn on the pipe l, and another arm or link, connected to a knobbed or handled ring or ferrule, n, fitted to turn on the hand-rod E. The steam-supply pipe is provided with a blow-off valve, o, arranged in a branch pipe thereof, and is designed to have a cut-off valve to arrest the action of the engine when necessary.

I claim and desire to secure by Letters Patent—

1. The combination, with the main casing of the engine and the piston-shaft D, provided on its outer end with the pinion f, of the bracket D', having its lower portion sleeved upon the shaft D and over the projecting bearing of the end plate of the casing A, and having a bearing h, on its upper edge, the shaft g, journaled in the bearing h, and provided at its outer end with means for holding the shank of boring-instrument, and the wheel f', fixed upon the shaft g and meshing with the pinion f, substantially as set forth.

2. The combination, with the steam-box A', having the ports a a', leading into the cylinder

B, of the exhaust-pipe l, extended into the steam-chamber b, the valve F', sleeved upon the inner end of pipe l, and arranged to alternately close and open the ports a a', and having its sleeve around the said pipe l extended to the outside of the steam-box, and means for turning the sleeve and valve, substantially as set forth.

3. In a steam-engine, the combination, with the reversing-valve F, of the toggled lever G, connected, one arm to a sleeve of the valve and another arm to a ring or ferrule, n, having a knob or handle, and adapted to turn upon the hand-rod E of the engine, substantially as and for the purpose set forth.

4. The combination, substantially as herein-before set forth, of the casing A, the stirrup j³, the handles E' E', supported upon laterally-extended arms K, the breast-plate j, provided with a hollow shank and sleeved upon the end of the head-plate, of cylinder A, the shaft D, provided with pinion f, the bracket D', supported upon the shaft D, the shaft g, journaled in the bracket D', and the gear-wheel f', supported upon the shaft g and meshing with the pinion f, substantially as set forth.

In testimony whereof I affix my signature in presence of two witnesses.

A. NOTEMAN.
